(Cl. D52—2)

FIG. 1

FIG. 2

FIG. 3

FIG. 4

FIG. 1 is a front elevation of a gasoline pump embodying my new design.

FIG. 2 is a right-hand side elevation thereof.

FIG. 3 is a left-hand side elevation thereof.

FIG. 4 is a top plan view thereof.

The rear of the gasoline pump is substantially the same in appearance as the front.

The dominant features of my design reside in the portions shown in full lines.

I claim:

The ornamental design for gasoline pump, as shown and described.
